TROWELS

Fred W. Tims, Jr., Stratford, Conn., assignor to The Camson Manufacturing Company, West Haven, Conn., a corporation of Connecticut
Filed Jan. 23, 1961, Ser. No. 84,256
4 Claims. (Cl. 15—235.6)

This invention relates to improvements in trowels and more particularly to the type of trowels used for laying tiles and applying mastic thereto, although it is not to be limited to this particular application.

Trowels for the purpose described customarily require various types and sizes of notches in the edges of the blades according to the different types of tile and the different mastics to be used therewith. It has been customary heretofore for workmen to use several different trowels, each with a distinctive notched edge, but this requires a multiplicity of implements which not only adds to the cost of the equipment furnished, but frequently the particular trowel needed may not be available.

One object of this invention is to provide replaceable blades, each with a distinctive and separate notched edge, having all of the standard notches usually required and which can be used selectively on the trowel without requiring multiple trowels in order to work with different tiles and mastics.

Another object of the invention is to improve the construction of a trowel so as to provide for the quick and simple insertion of replacement blades to enable blades having different characteristics to be used selectively, as required.

Still another object of the invention is to provide a trowel with an edge portion for the insertion and removal of replacement blades and which will tightly and securely hold a blade in place when fitted to the trowel.

These objects may be accomplished, according to one embodiment of the invention, by providing a trowel with a conventional body portion, but having, along one edge thereof, a spring pad tightly secured in overlapping relation with the edge of the body member for insertion of a replacement blade therebetween. The spring pad is so formed that its free edge portion is under compression to press tightly against the replacement blade and thereby hold the latter securely. It is preferred that a corner of the spring pad at one end thereof be turned upward or curled, to facilitate the insertion of the blade.

This embodiment of the invention is illustrated in the accompanying drawings, in which:

FIG. 1 is a perspective view of a trowel embodying this invention;

FIG. 2 is a front end elevation thereof;

FIG. 3 is a cross section therethrough, on the line 3—3 in FIG. 1, the blade being held in place within the clamping portion;

FIG. 4 is a similar view, showing the relation of the spring pad to the body member after removal of the blade; and

FIG. 5 is a detail perspective view, showing one end of the trowel.

The invention is illustrated in one embodiment as applied to a conventional form of trowel, such, for example, as may be used by tile setters. A trowel of this character comprises a body portion having a plate 1 upon which is secured a handle 2, by which the operator may manipulate the trowel.

The plate 1 may be somewhat narrower than the conventional base plate of the trowel and adapted for selective connection with a blade 3 extending along one lateral edge of the plate 1. A series of replaceable blades may be provided for each trowel having respectively different notched edges. These blades may be used selectively,

2

according to the tile or mastic with which the trowel is to be used.

Extending along one edge of the plate 1 of the trowel is a spring pad, generally indicated at 4. This spring pad 4 preferably extends throughout the length of the trowel and from the edge of the plate 1 inwardly in overlapping relation with the latter a sufficient distance to insure of secure clamping relation to a selected one of the replaceable blades 3. The inner edge portion of the spring pad 4 is spaced from the face of the plate 1 by a filler piece 5 interposed therebetween, and these parts are connected together in this example by rivets 6.

The spring pad 4 is preferably formed of very hard spring steel, so as not to be deformed readily in service and to maintain a tight gripping action on the selected blades. For this purpose, it is slightly humped or bent intermediate the width of the spring pad, as indicated generally at 7 in FIGS. 4 and 5, whereby the free edge portion of the pad which extends along the edge of the plate 1 is under compression, so as to apply pressure securely to the face of the blade 3 intermediate the width of the latter when the blade is inserted under the spring pad and against the filler piece 5.

In order to facilitate the insertion of the blade under the spring pad, a corner thereof is turned upwardly away from the face of the plate 1, as indicated at 8 in FIG. 5.

With each trowel, a plurality of blades may be provided, each with different sizes or shapes or notches, which makes one trowel the equivalent in function of several different trowels. Thus, the workman need not carry as much equipment, he is enabled to save the cost thereof, as well as the time of hand filing, and it has many advantages in service.

The blade is held tightly in place at the free edge of the trowel, but may be removed when it is desired to replace a blade, or a blade may be moved lengthwise in displaced relation relative to the body of the trowel, so as to get to close places around radiators and other points where it is difficult to get access with a conventional trowel. The blade may be reversed readily as, for example, in patching, with its notched edge pressed against the filler piece 5 and having a smooth-edged trowel for service.

The upturned edge portion 8 of the spring pad facilitates the insertion of the blade within the latter, pushing it into place and firmly against the filler piece, where it is held securely by the spring pad. The construction is such that the blade is tightly held in place during use, but may be replaced readily when desired. Normally, mastic will not get into the groove provided under the spring pad, but it is capable of being readily cleaned, if necessary.

While the invention has been illustrated and described in one embodiment, it is recognized that variations and changes may be made therein without departing from the invention as set forth in the claims.

I claim:

1. A trowel comprising a body portion including a base plate, a blade extending along an edge of the base plate and means for securing the blade to the base plate comprising a spring pad having one edge portion under compression and bearing upon a face of the base plate, the opposite edge portion of the spring pad overlapping the plate, a filler piece interposed between the last-mentioned edge portion and the base plate, and means securing the parts rigidly together.

2. A trowel comprising a body portion including a base plate, a separate blade extending along an edge of the base plate in overlapping relation therewith, a spring pad having an edge portion under compression and bearing yieldably on a lateral face of the blade opposed to the base plate holding the blade in place thereagainst, the

opposite edge portion of said spring pad extending in overlapping relation with the base plate, a filler piece interposed between the last-mentioned edge portion and the base plate and against which the edge of the blade bears, and means for securing the filler piece and spring pad to the plate.

3. A trowel comprising a body portion including a base plate, a separate blade extending along an edge of the base plate in overlapping relation therewith, a spring pad having an edge portion under compression and bearing yieldably on a lateral face of the blade opposed to the base plate holding the blade in place thereagainst, the opposite edge portion of said spring pad extending in overlapping relation with the base plate, a filler piece interposed between the last-mentioned edge portion and the base plate and against which the edge of the blade bears, and means for securing the filler piece and spring pad to the plate, said spring pad having an offset intermediate portion along the edge of the pad for causing the edge portion to bear initially against the base plate when a blade is not in place.

4. A trowel comprising a body portion including a base plate, a separate blade extending along an edge of the base plate in overlapping relation therewith, a spring pad having an edge portion under compression and bearing yieldably on a lateral face of the blade opposed to the base plate holding the blade in place thereagainst, the opposite edge portion of said spring pad extending in overlapping relation with the base plate, a filler piece interposed between the last-mentioned edge portion and the base plate and against which the edge of the blade bears, and means for securing the filler piece and spring pad to the plate, said spring pad having an upturned corner at one end thereof to facilitate insertion of the blade under the spring pad.
